UNITED STATES PATENT OFFICE

121,630

DESIGN FOR AN OFFSET PEDESTAL FOR
SCHOOL DESKS

William J. Bargen, Waukegan, Ill.

Application March 13, 1940, Serial No. 90,905

Term of patent 14 years

To all whom it may concern:

Be it known that I, William J. Bargen, a citizen of the United States, residing at Waukegan, in the county of Lake and State of Illinois, have invented a new, original, and ornamental Design for an Offset Pedestal for School Desks, of which the following is a specification, reference being had to the accompanying drawing, forming a part thereof.

In the drawing:

Figure 1 shows a perspective view of a pedestal embodying my new design.

Figure 2 is a sectional view taken on the line 2—2 of Figure 1.

Figure 3 is a detail side elevation of the base, the standard being broken away for convenience of illustration.

The configuration of the pedestal is the same on the opposite side as on the side shown in the drawing.

I claim:

The ornamental design for an offset pedestal for school desks, as shown and described.

WILLIAM J. BARGEN.
